UNITED STATES PATENT OFFICE.

MARTIN MATSON, OF MILWAUKEE, WISCONSIN, ASSIGNOR TO THE CUTLER-HAMMER MFG. CO., OF MILWAUKEE, WISCONSIN, A CORPORATION OF WISCONSIN.

MEANS FOR INSULATING LAMP-SOCKETS AND THE LIKE.

1,168,258.

Specification of Letters Patent. Patented Jan. 11, 1916.

Application filed January 28, 1914. Serial No. 815,043.

To all whom it may concern:

Be it known that I, MARTIN MATSON, a citizen of the United States, residing at Milwaukee, in the county of Milwaukee and State of Wisconsin, have invented new and useful Improvements in Means for Insulating Lamp-Sockets and the like, of which the following is a full, clear, concise, and exact description, reference being had to the accompanying drawing, forming a part of this specification.

This invention relates to electric lamp sockets, pendent switches, and the like, and more particularly to such devices wherein the insulating lining for the casing cap is carried by the socket base housed in the casing as disclosed in the co-pending application of Charles J. Klein, filed March 17, 1913, Serial No. 754,807.

One of the objects of the invention is to provide simplified and improved means for attaching a casing cap lining to an insulating base housed in the casing.

A further object is to provide an efficient snap locking means for releasably securing a resilient insulating member to a rigid insulating member.

Other objects and advantages will appear hereinafter.

In order to more clearly disclose my invention I have illustrated a preferred embodiment thereof in the accompanying drawing. It is to be understood, however, that the form shown is susceptible of modification and that the invention is capable of other embodiments.

In the drawing, Figure 1 is an elevational view of a lamp socket, partially in section; Fig. 2 is a side view of the conductor-carrying base provided with an insulating lining for the casing cap. Fig. 3 is a top view of the socket base; and Fig. 4 is a perspective view of the casing cap lining.

Referring more specifically to the drawing, a conventional casing comprising a metallic shell 1 and cap 2 is arranged to house and support an insulating base 3 which carries the current conducting parts of the socket device. Suitable means is provided for locking the parts of the casing together. An insulating lining 4 for the casing cap is mounted upon and carried by the socket base 3.

In the form shown, the insulating base is transversely divided into a lower section 5

and an upper section 6, having secured between the same a snap switch mechanism provided with a push-button operating member 7. A screw shell 8 is secured to the lower face of the base section 5 and a pair of terminal binding posts 9, for connection to line wires, are provided on opposite sides of the insulating base and preferably arranged on the section 5 at right angles to the push-button 7. Vertically extending conductor grooves 10 are provided in the sides of the upper section 6 in alinement with the binding posts 9. An annular flange 11 extends around the upper margin of the base 6 and is provided with oppositely disposed cut-away recesses 12 coinciding with the grooves 10.

The casing cap 2 carries a bushing 13 through which the line wires enter the casing for attachment to the binding posts 9. Such wires divide above the base 6 and snugly fit in the grooves 10 so that the bared ends may be readily fastened to the socket terminals.

As above mentioned, the insulating lining 4 which protects the cap 2 from accidental contact with the conductors, is carried by the rigid insulating base 6. The means of attachment shown between these parts comprises a pair of depending ears 14 on the fibrous lining which are adapted to snap into engagement with the lower surface on the flange 11 of the base. As shown, the ears or lugs 14 are substantially of the shape of an inverted T having a connecting shank 15 and a cross-head 16.

In wiring and assembling the device, the line wires may be threaded through the bushing 13, then through an aperture 17 in the insulating lining 4 and finally secured to the binding posts 9. The lining 4 is then snapped upon the base 6, as shown, the shank 15 of the lugs 14 fitting in the base recess 12 and the cross-head 16 engaging the lower face of the flange 11, thereby locking the lining against separation from and relative rotation on the base. When thus positioned the lining entirely covers the line wires and the ears 14 tend to retain the wires snugly in the conductor grooves 10 of the base. After the wiring is completed the device may be readily inserted in the casing so that the lining 4 snugly fits the interior of the cap and effectively insulates the same.

The base sections 5 and 6 and the lamp

shell 8 are preferably secured together by vertically extending screws 18 accessible from the top of the base. The heads of these screws may be suitably sealed with insulating wax, if desired, and barrier walls 19 may be provided on the base to additionally safe-guard against accidental contact between the line wires and the screws.

The shell 1 is lined with a tube 20 of insulating material, and, in the preferred form the margin 21 of the shell lining fits over the lugs 14 of the cap lining when the socket is assembled. The cap lining is then positively secured against accidental separation from the base and furthermore, in the case of pendent sockets, the cap lining may thus be employed as a strain relief for the line conductors by knotting the latter within the lining.

20. What I claim as new and desire to secure by Letters Patent is:

1. The combination with a lamp socket or similar casing including a cap, of a device provided with terminals for connection with line wires, and an insulating member carried by said device to insulate the line wires from said casing cap, one of said parts having a shoulder and the other having a resilient portion receiving said shoulder to secure the same together.

2. The combination with a metallic casing comprising a cap and shell having means for locking the same together, of an insulating base inclosed and supported within said casing, and an insulating lining of fiber-like material for said cap mounted on said base, said parts having snap engaging means, independent of said first-mentioned means, for securing said lining to said base.

40. 3. In a lamp socket or similar device, in combination, an insulating base having a peripheral transverse flange, said flange

having a vertical recess therein, and an insulating member of fibrous material having a marginal ear with a cross head and connecting portion, the head of said ear engaging a transverse face of said base flange and the connecting portion of said ear fitting in said flange recess to hold said member and said base in fixed relation.

4. In a lamp socket or similar device, in combination, an insulating base having a terminal binding post accessible from the side of said base for connection to a line wire and having a recess above said binding post for receiving said wire, and an insulating lining having a marginal portion overlying said base recess for holding said wire therein.

5. In a lamp socket or similar device, in combination, an insulating base having a binding post for connection to a line wire and a groove thereabove for receiving said wire, and an insulating cover having a resilient marginal portion engaging said base for securing the same together and overlying said groove for holding said wire therein.

6. In a lamp socket or similar device, the combination with a casing comprising a cap and shell, of a base therein for the current-carrying parts, an insulating member for said casing cap having attaching portions for engaging said base, and an insulating member for said casing shell fitting over said attaching portions of said first-mentioned insulating member for holding the same in engagement with said base.

In witness whereof, I have hereunto subscribed my name in the presence of two witnesses.

MARTIN MATSON.
